PETE CAPITO, OF WEIRTON, WEST VIRGINIA, ASSIGNOR OF ONE-HALF TO THOMAS L. SATTARELLI, OF WEIRTON, WEST VIRGINIA

ANTIBACKLASH MECHANISM FOR ROLLING-MILL TRAINS

Application filed January 25, 1930. Serial No. 423,484.

- This invention relates to anti-backlash mechanism for rolling mill trains, and it has for its object to provide an apparatus by means of which is materially, if not wholly, prevented the objectionable tendency on the part of the rolls of certain of the alined mills of a rolling mill train to chatter and whip about when heavy pieces of metal are being passed through other mills of the train.
- 10 As is well known to those familiar with the art, in rolling mill trains embodying four or more mills joined as ordinarily by means of spindles having their ends coupled by collars to the wabbles of the lower rolls of 15 said mills, much trouble is experienced on account of the whipping about and chattering, commonly termed "backlash", of the rolls of those mills of the train which are employed as finishing mills, usually located 20 remote from the engine, or driving mechanism. Those mills of the train located more or less closely adjacent to the driving mechanism—that is, the first two or three mills— 25 are usually employed as roughing mills, whereas those mills of the train located more remotely from the driving mechanism are usually employed as finishing mills, though, as is well known, this arrangement may be varied. The vibration and shocks which 30 result from passing heavy material through the roughing mills are communicated in a greatly aggravated, intensified, or augmented degree or form to the finishing mills, setting up in the latter violent chattering, 35 and vibrating movements, or backlash, which seriously impairs the finishing action thereof, resulting in the sheets of metal acted upon by the rolls of said finishing mills being marred, if not, actually ruined.
- 40 As hereinbefore stated, it is the object of the present invention to provide a mechanism whereby the objectionable backlash in the finishing mills of a roll train is practically eliminated.
- 45 In describing the invention in detail, reference is herein had to the accompanying drawings, in which—

Figure 1 is a top plan view of a rolling mill train embodying my invention;

50 Figure 2 is a view of the invention, partly

in front elevation and partly in section, showing the same introduced between a roughing mill and a finishing mill;

Figure 3 is a sectional elevation on line 3—3, Fig. 2;

Figure 4 is a section on line 4—4, Fig. 3;

Figures 5 and 6 are enlarged views in side elevation and top plan, respectively, of the cap-plate; and—

Figures 7 and 8 are views in top plan and 60 end elevation, respectively, of the top brass, or rider block.

Referring to said drawings, the reference numerals 1, 2 and 3 designate generally 65 roughing mills and 4 a finishing mill, said mills being arranged in a train and adapted to be driven by any suitable power mechanism, as an engine 5. Interposed in the train between the roughing mill 3 and the finishing mill 4 is the anti-backlash mechanism 70 which constitutes the present invention, the same comprising a lower roll 6 and an upper roll 7 journaled in housings 8.

The housings of said anti-backlash mechanism may be identical with those employed 75 in the various mills in the train, as may also the upper roll 7 be identical with the rolls of said mills; or, a worn-out mill roll may be utilized as the upper roll of said mechanism.

The lower roll 6 of said mechanism has the 80 usual form of roll necks 9, but, instead of being provided with the usual roll wabbles through which connection might be made with the alined lower rolls of adjacent mills, said roll 6 has formed integral therewith at 85

each of its opposite ends a long stem 10 having on its end a wabble of the usual form adapted to be directly connected by a collar 12 to the wabble of the lower roll of the adjacent mill. Otherwise expressed, the stems 90

10 directly connect to the lower rolls of adjacent mills without the interposition of the usual spindles 13 by means of which the lower rolls of adjacent mills of the train are 95 coupled. Thus, the roll 6 is at all times maintained relatively much less flexible than are the usual spindle-coupled rolls of mills arranged in a train, and, therefore, is not so readily caused to move about or chat-

ter by violent shocks or vibratory movements set up in adjacent mills.

The necks 14 of the upper roll 7 have seated thereon bearing brasses or blocks 15 which carry thereon a plurality of integral or rigidly mounted upright posts 16, each of which is encircled by a heavy spiral spring 17; and superposed on said springs is a cap plate 18 having therein holes 19 through which extend the upper ends of said posts. A boss 20 formed centrally on the upper face of said cap plate has therein a socket 21 adapted for receiving in seated relation thereto the lower end of a screw 22 which is mounted in the housing. Said screws 22 are adapted for manipulation to effect adjustment of the tension placed upon the springs 17, thus to regulate the pressure exerted by the upper roll 7 upon the lower roll 6. Said springs when placed under heavy compression serve in the capacity of shock absorbers, tending to steady the rolls 6 and 7 and, consequently, to prevent transmission to the finishing mill or mills of movements set up in the rolls of the roughing mills by passage through the latter of heavy pieces of metal and which movements would otherwise be translated into the objectionable backlash to the finishing mill rolls hereinbefore referred to.

In practice, not only do the tension springs 17 act effectively to absorb shocks transmitted to and through the rolls 6 and 7, and thus to exert upon the roll 6 a steady force for preventing the transmission to the rolls of the finishing mills of violent shocks which would tend to produce chattering of said rolls, but, as hereinbefore explained, the relatively reduced flexibility between said roll 6 and the thereto-adjacent mills resulting from the provision of integral stems 10 renders said roll less liable to be affected by and, therefore, to transmit such shocks, or vibratory movements.

45 What is claimed is—

1. In a rolling mill train embodying coupled roughing and finishing mills, an anti-backlash mechanism introduced between said roughing mills and said finishing mills, said mechanism comprising roll housings, upper and lower rolls journaled in said housings, the lower roll having integral stems at its opposite ends adapted to be coupled directly to the mills at opposite sides thereof, springs superposed over said upper roll, and means for adjusting the compression of said springs to regulate the pressure exerted by said upper roll on said lower roll.

2. In a rolling mill train embodying coupled roughing and finishing mills, an anti-backlash mechanism introduced between said roughing mills and said finishing mills, said mechanism comprising roll housings, upper and lower rolls journaled in said housings, the lower roll having integral

stems at its opposite ends adapted to be coupled directly to the mills at opposite sides thereof, and means whereby adjustable yielding pressure may be applied to said upper roll.

3. In a rolling mill train embodying coupled roughing and finishing mills, an anti-backlash mechanism introduced between said roughing mills and said finishing mills, said mechanism comprising roll housings, upper and lower rolls journaled in said housings, the lower roll having integral stems at its opposite ends adapted to be coupled directly to the mills at opposite sides thereof, bearing blocks seated upon the necks of said upper roll, springs mounted on said blocks, cap plates mounted on said springs, and adjusting means whereby varying pressures may be applied to said cap plates for regulating the steady pressure applied to said lower roll through said upper roll.

In testimony whereof, I affix my signature.

PETE CAPITO.
